United States Patent Office

Des. 232,230

Patented July 30, 1974

232,230

DESK TELEPHONE

James J. Davis, New Cumberland, and William R. De Lozier, Camp Hill, Pa., assignors to International Telephone and Telegraph Corporation, Nutley, N.J.

Filed May 9, 1972, Ser. No. 251,849

Term of patent 14 years

Int. Cl. D14—03

U.S. Cl. D26—14 A

Fig. 1

Fig. 2

Fig. 3

FIG. 1 is a perspective view taken from the front, top and right side of a desk telephone showing our new design;

FIG. 2 is a top view of a desk telephone showing our new design; and

FIG. 3 is a left side view thereof.

The broken line indicia representing conventional numerals is shown for illustrative purposes only.

We claim:

The ornamental design for a desk telephone, substantially as shown and described.
